UNITED STATES PATENT OFFICE.

LOUIS M. MUSLINER, OF NEW YORK, N. Y., ASSIGNOR TO GEISMAN, MUSLINER AND BRIGHTMAN, INC., OF NEW YORK, N. Y., A CORPORATION OF NEW YORK.

DESIGN FOR LEATHER OR SIMILAR ARTICLE.

Application filed December 12, 1924. Serial No. 11,673. Term of patent 7 years.

To all whom it may concern:

Be it known that I, LOUIS M. MUSLINER, a citizen of the United States, and a resident of the city of New York, borough of Manhattan, in the county and State of New York, have invented a new, original, and ornamental Design for Leather or Similar Article, of which the following is a specification, reference being had to the accompanying drawing, forming part thereof.

The figure is a plan view of a sheet of leather, illustrating my new design.

I claim:

The ornamental design for leather or similar article as shown.

LOUIS M. MUSLINER.
